(57) **CLAIM**

The ornamental design for a slider, as shown and described.

DESCRIPTION

FIG. 1 is a perspective view of a slider showing new design;
FIG. 2 is a top view thereof;

FIG. 3 is a bottom view thereof;

FIG. 4 is a front view thereof, the rear view being identical;
and,

FIG. 5 is a left side view thereof, the right side view being
identical.

The broken lines shown represent unclaimed subject matter
and form no part of the claimed design.
